UNITED STATES PATENT OFFICE.

FRANK A. HALLECK, OF MICHIGAN CITY, INDIANA, ASSIGNOR TO SULLIVAN MACHINERY COMPANY, A CORPORATION OF MASSACHUSETTS.

FORGING MACHINE.

Original application filed July 30, 1920, Serial No. 400,121. Divided and this application filed September 9, 1924. Serial No. 736,794.

This invention relates to forging machines. It has for its object to provide an improved forging machine. A further object is to provide improved controlling means for several of the elements comprising a forging machine such as swaging and upsetting mechanisms and clamping mechanism. More specifically, the object of the invention is to provide improved means whereby the upsetting mechanism will be rendered inoperative until the clamping mechanism is in full closed position, thus avoiding danger to the operator due to the fact that the upsetting mechanism which comprises a pneumatic hammer might drive a work piece outwardly from the clamping mechanism before the piece is securely held.

In the accompanying drawings I have shown for purposes of illustration one form 20 which my invention may assume in practice.

In these drawings,

Fig. 1 is a side elevation of a forging machine with the controlling lever cover removed.

Fig. 2 is a vertical longitudinal section through the distributing valve.

Fig. 3 is a longitudinal section on line 3—3 of Fig. 1.

Fig. 4 is an enlarged partial sectional view 30 of the improved foot control valve for the swaging motor.

In the illustrative embodiment of my invention I have shown the same incorporated in a usual type of drill sharpening machine comprising a base 1 having a swaging motor 2, clamping mechanism 3, and upsetting mechanism 4. In my copending application, Serial No. 400,121, filed July 30, 1920, of which this application is a division, the swaging mechanism 2 is offset from the longitudinal axis of the upsetting mechanism 4 so that when a drill steel, which this machine is particularly adapted to work upon is clamped by the mechanism 3 no particular harm would be done in case the swaging mechanism 2 should accidentally be operated. My present invention is directed more specifically to means for insuring operation of the clamping mechanism 3 before operation 40 of the upsetting mechanism 4. A fluid operated piston type motor, generally indicated at 5, is adapted to actuate the clamping mechanism 3 as by suitable means including

rods 6. In my improved mechanism the base or frame 1 is provided adjacent the rear end 55 of one side thereof with a supply chest generally indicated at 7 and to this chest a live fluid, preferably compressed air, connection 8 is led. The lower portion of the live fluid chest is provided with an oil pocket 9 and air in passing to a valve chest 10 blows over 60 the top of the oil and entrains a small portion thereof, thereby assisting in the supply of lubricant to any of the desired working parts. Within the valve chest 10 which communicates by means of a passage 11, see Fig. 2, with the fluid pressure supply chest 7, is arranged a valve 12 which is generally rectangular in shape and which is further provided with a U-shaped passage 13 extending 70 therethrough, and opening at the lower face thereof, that is, the face adjacent the valve seat. This valve is reciprocable across a valve seat 14 in which are formed a series of ports 15, 16, 17 and 18, these ports leading 75 respectively to the foot valve, later described, and to the clamping motor, the dolly actuating motor, and to the exhaust. The exhaust passage leads directly to a chamber formed in the interior of the frame which constitutes 80 a suitable exhaust reservoir. With the parts in the position shown in Fig. 3 the clamping mechanism is connected with the exhaust, the horizontal hammer or dolly hammer supply is closed and the port 15 which leads to the 85 foot valve is open, as is the case at all times as the limited length of the valve travel will not permit closing of this port. From the port 15 a pipe 19 leads downward to the foot valve mechanism 20 which is clearly shown 90 in Fig. 4. As will be noted, this valve is divided into two chambers by means of a partition 21 in which a valve seat 22 is formed, the upper chamber communicating directly by the pipe 23 with the cylinder of the clamping motor and the lower chamber which is normally kept from communication with the live air by the valve 24, seated upon the valve seat 22, is provided with a connection 95 25 which connects with a suitable pipe leading to the valve chest of the vertical motor. The foot valve 24 is operated by a treadle 26 which is pivoted at 27 to the frame and operates a valve stem 28 of the foot valve 24. To prevent accidental operation of the 100 treadle 26, I have provided an inverted U- 105

shaped shield 29 covering the treadle 26 and supported by the bracket 30 projecting from the side of frame 1.

To operate the valve 12, I employ a valve 5 stem 31 which is actuated by a bell crank lever 32 provided with an operating handle 33 projecting to the front and one side of the frame 1 and also provided with a depending arm 34 adapted to cooperate with 10 a vertical stop member 35 secured to the lower crosshead 36 of the clamp mechanism. It is to be noted that the crosshead 36 is secured to the lower ends of the vertical rods upon the upper ends of which is mounted 15 the movable member of the clamping mechanism 3 and that the connection between the clamping mechanism and the motor 5 is through suitable toggle links, one end of which is connected to the crosshead 36. Inasmuch as the detailed structure of all the 20 several mechanisms is disclosed in my co-pending application, it is not thought necessary to go into detail here inasmuch as the present invention merely relates to the controlling means for said mechanisms.

In view of what may be called first position, the valve 12 is in approximately the 25 position shown in Fig. 3 and maintains both ports 16 and 17 closed, that is, both the clamp operating and the dolly motor controlling connections are closed to the live fluid. When the valve is in this position, the lever 33 is raised considerably from the 30 position disclosed and the lever 34 is at an equal distance on the opposite side of the 35 vertical member 35 from that which it now occupies to the rear of that lever. It will be further noted that with the parts in that 40 position, the clamp mechanism is in open position, the pistons thereof being at the extreme left hand ends of their cylinders and the clamp raised as high as possible. Accordingly, the member 35 is above and to the left of the bottom of arm 34. As disclosed in my co-pending application the 45 motor 5 comprises large and small cylinders 37 and 37' within which positively connected pistons 38 and 39 reciprocate. Pressure is continuously admitted to the right hand side 50 of the piston 39 to release the clamping mechanism but when the clamping mechanism is operative said pressure is overcome by the pressure acting on the left hand side of the large piston 38. It should 55 be noted however that in another position of the arm 34 and accordingly the valve 12, port 16 is connected by means of a suitable passage with a port 40 communicating with the large cylinder bore 37 and through which 60 live fluid is passed to act upon and force the piston 38 against the pressure on piston 39 over to the other end of its stroke. When the lever 33 is depressed, it can only move a certain distance, namely, until the arm 34 65 thereof collides with the member 35 and dur-

ing this movement the valve 12 is permitted to move only to a sufficient degree to fully open the port 16 leading to the clamping mechanism. Accordingly, further movement is impossible until the clamp is closed 70 and the valve cannot be moved so far as to start the dolly motor by the admission of fluid to the port 17 until after the drill steel which is to be operated upon by the dolly is securely clamped by the clamping mechanism. It will thus be seen that danger of injury, due to actuation of the dolly prior to the clamping of the steel is avoided. It will be noted also that the valve chest is provided with an upwardly extending chamber 40 which communicates with a chamber 41 in which the valve 42 is located and which 75 conducts the supply of air to the hole opening pinning mechanism 43.

While I have in this application specifically described one form which my invention may assume in practice, it will be understood that this form of the same is shown for purposes of illustration and that the invention may be modified and embodied in 80 various other forms without departing from its spirit or the scope of the appended claims.

What I claim as new and desire to secure by Letters Patent is:

1. In a forging machine having a plurality of mechanisms, means for sequentially controlling said mechanisms to effect operation thereof in a fixed predetermined order including an actuating lever and means for controlling movement thereof directly engaging the same, said controlling means being movable with respect to the lever and being engageable thereby only in some of their relative positions.

2. In a forging machine having a plurality of cooperating fluid-operated mechanisms, a fluid controlling valve, and means for sequentially controlling said mechanisms to effect operation thereof in a fixed predetermined order including an actuating lever 100 for said valve and means for controlling movement thereof directly engaging said lever, said lever and means being relatively movable and engageable only in some of their relative positions.

3. A forging machine having a plurality of work-performing elements, and means for controlling the same in a fixed predetermined order including a lever and means directly carried by one of said elements and directly 110 engaging the lever for governing its movement.

4. A forging machine having a plurality of work-performing elements, and means for controlling the operation of the same in a fixed predetermined order including a lever and means for preventing movement of said lever directly engaging the lever in one position of said means but not in another, said controlling means during a 115

part of its operation being dependent upon the length of time of the initial operation of one of said elements.

5. A forging machine having a plurality of work-performing elements, and means for controlling the same in a fixed predetermined order including a lever having an arm which has an immovable relation to said lever, and means carried by one of said elements and movable therewith for directly engaging said arm to prevent movement thereof.

6. A forging machine having a plurality of movable work-performing elements, and means for controlling the same in a fixed predetermined order including a lever and a plurality of elements carried directly and solely by said lever and by certain of said work-performing elements respectively and having relative movement, said elements cooperating directly to prevent lever movement.

7. The combination with a forging machine having power-actuated work-performing means, a movable member for controlling power therefor, and a lever for controlling movement of said member, of means for controlling movement of said lever including relatively movable cooperating parts carried directly and solely by the lever and work-performing means respectively, said member, lever and parts being disposed in a single plane.

8. In a forging machine, a plurality of fluid-operated elements, means for sequentially operating the same in a fixed predetermined order including a valve adapted to have a plurality of positions, a lever for controlling the same having a portion providing a surface angularly disposed to the longitudinal axis of said lever, and a member adapted to engage said surface when said valve is in its first position but not when said valve is in a predetermined subsequent position.

9. In a forging machine having a movable power-moved work-performing element, means carried thereby providing a controlling surface, and controlling means for said element including a controlling member having a fixed pivot and adapted to have its pivotal movement limited by its direct engagement with said surface during movement of said element.

55 10. A forging machine having work-performing means including a power-movable element, abutment means carried by said element, and controlling means for said element including a movable controlling member having a fixed pivot and having its movement limited by its direct engagement with said abutment means during certain stages of movement of said element.

60 11. A forging machine having work-performing means including a power recipro-

cable element, abutment means carried directly thereby, and controlling means for said element including a controlling member having a fixed pivot and engaging said abutment means directly during certain stages 70 of movement of said element and moving across the path of movement of said abutment during other stages.

12. In a forging machine, a power movable element having a controlling surface associated therewith, and means for controlling said element including a controlling member adapted to engage said surface directly and having a fixed pivoting point, said member being adapted to be swung 75 about its fixed pivot in an arcuate path transversely of the path of movement of said surface.

13. In a forging machine, a plurality of power-operable mechanisms, means for controlling operation of the same in a fixed predetermined order including a member movable substantially in a straight path, and a second member having a fixed pivot to allow direct engagement with said first 80 member when the latter is at one end of its path but not at the other end thereof, and means whereby said engagement prevents operation of one of said mechanisms.

14. In a forging machine having a plurality of fluid-operated elements, a valve mechanism for controlling the same comprising a valve and a valve chamber into which there open directly a plurality of ports, certain of said ports being adapted 100 to be wholly closed by said valve while the remainder is adapted to be always in communication with a source of live pressure fluid through said chamber, certain of said open and closed ports being in communication 105 with said fluid-operated mechanisms.

15. In a forging machine having a plurality of fluid-operated elements, and means for controlling fluid flow to said elements including means whereby one of said elements is continuously supplied with live pressure fluid acting thereon invariably in one direction as long as fluid is supplied to said forging machine, and means for controlling fluid flow to another of said elements 110 from the line which communicates with the continuously supplied element.

16. In a forging machine comprising a plurality of fluid-operated elements, means for continuously supplying one of the same 120 with live pressure fluid acting thereon invariably in one direction as long as fluid is supplied to said forging machine, and means for supplying another of said elements with pressure fluid from the line which communicates with said first-mentioned element, said latter means comprising a valve housing having a plurality of chambers and a transverse partition therein, and a valve 125 controlling fluid flow through said partition. 130

17. In a forging machine comprising a plurality of fluid-operated elements, means for continuously supplying one of the same with live pressure fluid acting thereon invariably in one direction as long as fluid is supplied to said forging machine, and means for supplying another of said elements with pressure fluid from the line which commu-

nicates with said other element, said latter means comprising a valve housing having a plurality of chambers and a transverse partition therein, a valve controlling the flow of fluid through said partition, and a foot-controlled lever for controlling said valve.

In testimony whereof I affix my signature.
FRANK A. HALLECK.
